DETECTOR FOR WARP STOP MOTION

William A. Blanchard, Millbury, Mass., assignor to Crompton & Knowles Loom Works, Worcester, Mass., a corporation of Massachusetts

Application May 26, 1951, Serial No. 228,393

10 Claims. (Cl. 139—353)

1

This invention relates to improvements in detectors or drop wires for warp stop motions and it is the general object of the invention to provide a cheap detector made of bent wire.

The usual detector for drop wires is made from flat sheet metal by a punching operation which leaves a burr at the upper end of the thread slot in position to abrade a warp thread on which the detector rests. This burr must be removed by a grinding and polishing operation which is expensive and does not always remove all of the burr.

It is an important object of the present invention to make the detector of pieces of wire at least one piece of which has a rounded surface and is bent so as to provide an eye or the like for the warp thread. The roundness of the wire presents a smooth surface for engagement with the warp thread and chaffing or abrasion of the latter is avoided.

Many warp stop motions operate with separator bars to divide the drop wires into several banks. These bars are usually in position to support the warp threads on their upper edges and it is a further object of the invention to provide a detector formed with a primary outer wire bent to a shape which will enable it to engage adjacent separator bars, and provide a secondary wire within the outline of the primary wire formed with the aforesaid thread eye.

It is customary to have an upwardly extending slot in the bottom of a warp stop detector to receive a warp thread and it is a further object of the invention to provide a detector formed with a primary outer wire bent to a shape which will enable it to engage adjacent separator bars, and provide a secondary wire preferably within the outline of the primary wire and formed with a downwardly opening thread slot communicating with the thread eye.

A form of electric warp stop motion which has gone into general use employs a contact bar having two electrodes normally insulated from each other but electrically connected by a falling detector. It is a further object of the invention to provide a detector as described hereinbefore having the upper parts of the primary wire shaped to define a slot to receive a contact bar and having portions of the wire bent toward each other into the slot for cooperation with the electrodes of the contact bar.

In order that the eye of the secondary wire may be held in fixed position with respect to the primary wire it is a further object of the invention to form the eye so that it can be welded or otherwise secured to adjacent parts of the

2

primary wire at points below the upper part of the eye, thereby preventing any roughness which may accompany joining of the two wires from being in position for contact with the warp thread.

The primary and secondary wires are preferably of circular cross section in their original form and are then rolled or pressed to reduce their thickness, but this latter operation will not be necessary in all instances.

In order that the invention may be clearly understood reference is made to the accompanying drawings which illustrate by way of example the embodiments of the invention and in which:

15 Fig. 1 is a front elevation of part of a warp stop motion showing detectors made according to the present invention.

Fig. 2 is an enlarged vertical section on line 2—2, Fig. 1;

20 Fig. 3 is an enlarged vertical section on line 3—3, Fig. 2;

Fig. 4 is an enlarged horizontal section on line 4—4, Fig. 2;

25 Fig. 5 is an elevation of the primary wire forming part of the detector;

Fig. 6 is an elevation of the secondary wire forming part of the detector, and

30 Figs. 7 and 8 are vertical sections on lines 7—7 and 8—8, respectively, of Figs. 5 and 6 before the wire is rolled to be flattened as indicated in Fig. 3.

Referring to Figs. 1 and 2, the warp stop motion includes an electric contact bar 1 and horizontally spaced separator bars 2 and 3 below the contact bar. The warp threads W will ordinarily extend across and may rest on the top edges of the separator bars 2 and 3 and feed toward the weaving instrumentalities of a loom. The contact bar 1 is supported with respect to the separator bars by a support 5 which may be held to appropriate structure not shown by means of a bolt 6. The contact bar includes an inner insulated electrode 7 and an outer generally grounded electrode 8, and these electrodes are separated by a strip of insulation 9. The

40 electrode 8 has a rib 10 and the electrode 7 has a part 11 thereof projecting beyond the outline of the electrode 8, to the right as viewed in Fig. 2. The detector forming the subject matter of the present invention is designated generally at 45 D and comprises primary and secondary wires 15 and 16, respectively, which are shaped as shown in Figs. 5 and 6. These wires are preferably round in cross section in their original form, as indicated in Figs. 7 and 8.

50 The primary wire 15 is bent to provide ver-

tical side members 20 and 21 which are separated horizontally from each other to define a slot 22 for the contact bar 1. The upper ends of the members 20 and 21 are joined by a bend 23 of the wire 15, and opposite parts of members 20 and 21 below bend 23 are bent toward each other into slot 22 as at 24 to provide for engagement with the rib 10 and the extended part 11 of the insulated electrode 7.

The members 20 and 21 have portions 25 and 26 thereof bent away from each other to provide a widened part of the primary wire for engagement with the separator bars, as will be apparent from Fig. 2. The members extend downwardly from their portions 25 and 26 and are drawn toward each other as at 27 and then extend downwardly with parallel parts 28 spaced from each other. The lower ends of the members 20 and 21 may be bent in opposite directions as at 29.

The secondary wire 16 is bent to define a rounded warp thread receiving eye 30 formed by upwardly curved parts 31 and 32 of the wire. The eye has an opening 33 at the lower side thereof which communicates with a thread slot 34 lying between downwardly extending side members 35 and 36. The lower ends of these latter members are bent as at 37 to facilitate entry of a warp thread into slot 34.

The upper ends of portions 25 and 26 of the primary wire are bent as at 40 and 41 to conform substantially to the upper part of the eye in the secondary wire, as indicated in Fig. 2. The primary and secondary wires are secured to each other, as by welding, and lie in a common plane. The two wires may be welded together at 42 to join the portion 25 and 26 of the primary wire and the upwardly curved parts 31 and 32 below the top of the eye so that even though some roughness should be left in the wire due to welding it will be below a thread supporting the detector. The parts 28 of the primary wire lie along and outside of the members 35 and 36 of the secondary member and may be welded to the latter as at 44.

After the primary and secondary wires have been bent as described they can if desired be subjected to a rolling operation which will flatten them so that it will have sides 45 and 46, see Fig. 3. In the flattening or rolling operation some of the original curvature of the wire is retained, particularly that part indicated at 47 on the under side of the top part of the secondary wire facing the eye 30. This curved part will be smooth and a warp thread can pass under it without abrasion, and no grinding or polishing operation will be necessary to form the surface 47 as has been necessary in the past when drop wires have been punched from flat stock.

From the foregoing it will be seen that the invention sets forth a simple and cheap form of detector for warp stop motion comprising two wires secured to each other and lying in the same plane and bent so as to define a slot 22 in the upper part of the detector for the contact bar. The secondary wire is bent to define an eye 30 to receive a warp thread, and those parts of the wire defining the eye are between the portions 25 and 26 of the members 20 and 21. The portions 25 and 26 of the primary wire are provided for engagement with the separator bars. Those parts of the secondary wire defining the eye are secured to the primary member at points below the top of the eye, and lower adjacent parts of the two wires may be secured together. The preferred method of attaching the two wires is by welding, but 75

the invention is not limited to this manner of securing them together. After the wires have been bent to the form shown for instance in Figs. 5 and 6 they may be rolled or pressed to reduce their thickness. The welding or other procedure to attach the two wires together may be done either before or after the rolling operation.

Having now particularly described and ascertained the nature of the invention and in what manner the same is to be performed, what is claimed is:

1. A detector for a warp stop motion including an electric contact bar, said detector comprising a piece of wire having side members the upper parts of which form a slot to receive the contact bar, and a second piece of wire secured to and between said side members formed with a rounded eye for a warp thread and having the parts thereof below the eye forming a thread receiving slot opening into said eye.

2. The detector set forth in claim 1 wherein parts of said members extend below said eye and lie along the parts of the second piece of wire which form the thread slot.

3. The detector set forth in claim 1 wherein the part of the second piece of wire in which the eye is formed is secured to adjacent parts of said members.

4. The detector set forth in claim 1 wherein the parts of the second piece of wire which form the thread slot are secured to the adjacent parts of said members.

5. The detector set forth in claim 1 wherein said upper parts of the side members are bent toward each other for cooperation with the contact bar.

6. A detector for a warp stop motion having horizontally spaced warp thread supporting separator bars, said detector comprising a primary piece of wire having vertical members portions of which are bent away from each other for engagement with the separator bars, a secondary piece of wire secured to the primary wire formed on the upper part thereof with a rounded warp thread eye having an opening in the bottom thereof and located between said portions of the primary wire, said secondary wire having spaced parts thereof depending from the eye to form a thread slot communicating with said opening.

7. The detector set forth in claim 6 wherein the part of the secondary wire forming said eye is welded to said portions of the vertical members.

8. A detector for a warp stop motion having horizontally spaced warp supporting separator bars, said detector comprising a piece of wire having side members in a vertical plane joined at their upper ends and having portions thereof below said upper ends bent away from each other for engagement with said separator bars, said members extending below said portions and having parallel horizontally spaced parts between which a warp thread can move upwardly toward said portions, and a second piece of wire secured to said portions having upwardly extending curved parts to form a warp thread receiving eye between said portions open at the bottom thereof to receive a warp thread.

9. A detector for a warp stop motion having horizontally spaced warp supporting separator bars, said detector comprising a primary wire having side members in a vertical plane joined at their upper ends and having portions thereof below said upper ends bent away from each other for engagement with said separator bars, and a

secondary wire having upwardly extending curved parts to form a warp thread receiving eye between said portions, the lower portions of said upwardly curved parts of the secondary wire being secured to said side members below the top 5 of said thread receiving eye.

10. A detector for a warp stop motion having horizontally spaced warp supporting separator bars, said detector comprising primary and secondary pieces of bent wire both lying in the same vertical plane, the primary wire having side members portions of which are bent away from each other for engagement of said separator bars, and

the secondary wire being located between and secured to said members and having a part thereof bent to form a warp thread eye between said portions and in said vertical plane.
